UNITED STATES PATENT OFFICE.

VONLEY V. McCONNELL, OF CINCINNATI, OHIO.

DOOR-GAUGE CLAMP.

Application filed May 13, 1924. Serial No. 713,006.

To all whom it may concern:

Be it known that I, VONLEY V. McCONNELL, a citizen of the United States, residing at Cincinnati, in the county of Hamilton 5 and State of Ohio, have invented certain new and useful Improvements in a Door-Gauge Clamp, of which the following is a specification.

This invention relates to door gauge 10 clamps and it consists in the novel features hereinafter described and claimed.

An object of the invention is to provide 15 a clamp mechanism of simple structure adapted to be applied to the soffit board of a window or door frame and is intended to hold the head board of the framing in proper position with relation to the jambs or stiles in order that the head boards may be properly marked off and cut to fit snugly 20 in the window or door frame and with relation to the jamb boards.

In the accompanying drawing:—

Figure 1 is a side elevational view of the 25 upper portion of a window or door frame with the gauge applied to the soffit board.

Figure 2 is an enlarged transverse sectional view of the soffit board with the gauge and clamp applied.

Figure 3 is a perspective view of a plate 30 used in the gauge clamp.

As illustrated in the accompanying drawing, the soffit board of the window or door frame is indicated at 1, the jamb board at 2 and the head board at 3. The gauge clamp 35 comprises a pair of rectangular boxes 4, each provided at its inner side with a fixed bolt 5 having a threaded end portion 6. A turn buckle 7 engages the threads 6 of the bolts 5 and serves as means for adjustably connecting the said bolts together in a usual manner. The boxes 4 are provided at the 40 upper edges of their inner sides with outwardly disposed flanges 8 adapted to engage under the lower surface of the soffit board 1 when the gauge clamp is applied thereto.

Rectangular boxes 9 are mounted for telescopic movement in the boxes 4 and threaded shafts 10 are journaled in the bottom of the boxes 4 and their upper portions are threaded through the bottoms of the boxes. The boxes 9 are provided at their inner sides with vertically disposed slots 11 through which studs 12 pass, the said studs being fixed to the inner walls of the boxes 4. Set 50 screws 13 are threaded through the outer walls of the boxes 4 and when tightened are

adapted to engage against the outer surfaces of the outer walls of the boxes 9 whereby the boxes 9 are fixed with relation to the boxes 4. Plates 14 are housed within the boxes 9 and disposed parallel with the inner walls thereof and in close proximity thereto. The plates 14 are provided at their inner sides with prongs 15 which pass through the inner walls of the boxes 9 and which are adapted to engage in the edges of the soffit board 1 as best indicated in Figure 2 of the drawing. The plates 14 are provided with slots 16 which register with the slots 11 and the studs 12 pass through the slots 16. Wing nuts 17 are screwed upon the inner ends of the studs 12 and bear against the inner faces of the plates 14 and serve to hold the said plates 14 in close contact with the inner surfaces of the inner walls of the boxes 9. The upper portions of the boxes 9 project above the upper edges of the boxes 4 when the gauge clamp is applied to the soffit board and the upper edges of the boxes 9 are disposed in alignment with the upper surface of the soffit board 1. Therefore when the boxes are applied to the soffit board and the head board is rested upon one edge upon the upper edges of the boxes 9, the end portions of the head board 3 will be disposed across the jambs 2 in proper relation to the said soffit board and the jambs and may be readily marked off for cutting to fit between the jambs or to provide a mitre joint between the head board and the jamb board as is desired.

Having thus described the invention, what I claim is:—

1. A clamp gauge adapted to be applied to a soffit board comprising boxes provided at their inner sides with threaded bolts, means for drawing the bolts toward each other, other boxes slidably mounted in the first mentioned boxes, means for adjusting the inner boxes with relation to the outer boxes and plates adjustably mounted in the inner boxes.

2. A gauge clamp comprising an outer box, an inner box slidably mounted therein and provided at its side with openings, means for holding the inner box at an adjusted position with relation to the outer box, a plate mounted in the inner box and having prongs passing through the side openings of the inner box and means for securing the plate with relation to the inner box.

3. A gauge comprising an outer box, an inner box adjustably mounted in the outer box and provided at its side with openings, means for securing the inner box with relation to the outer box, the inner box being provided at its side with a slot, a stud carried by the outer box and passing through said slot, a plate located in the inner box

and having prongs which pass through the openings thereof, said plate being provided with a slot adapted to register with the slot in the inner box, and means for securing the plate with relation to the inner box. 10

In testimony whereof I affix my signature.

VONLEY V. McCONNELL.
